UNITED STATES PATENT OFFICE.

PHILEMON O. DICKINSON, OF NEWARK, NEW JERSEY, ASSIGNOR TO UNGER BROTHERS, OF SAME PLACE.

DESIGN FOR A BACK AND HANDLE FOR MIRRORS, &c.

SPECIFICATION forming part of Design No. 26,422, dated December 22, 1896.

Application filed October 10, 1896. Serial No. 608,528. Term of patent 31 years.

To all whom it may concern:

Be it known that I, PHILEMON O. DICKINSON, a citizen of the United States, residing at Newark, in the county of Essex and State of New Jersey, have invented and produced a new and original Design for Backs and Handles of Mirrors and Similar Articles, of which the following is a description, reference being had to the drawing accompanying and forming a part of the same.

The general outline of the back is circular, and the general outline of the handle is of lyrate form.

The motive or style of the surface decoration of the back of the mirror is of conventionalized rococo order, consisting of a broad band practically covering the entire surface of the back except for the relatively small plain or bare surface A and composed of an enrichment of irregularly-repeated scrolls, shells, flowers, and leaves. Thus B B indicate scrolls of differing design surrounding the plain space A, and C C are scroll-shells in support of the same, while D is a basilar scalloped shell, E various foliate shells, and F various forms of flowers, all variously interwoven and joined together by a variety of

scrolls, such as G, as shown in the accompanying drawing.

The characteristic ornamentation of the handle consists of flowers H, located on the face of the lower portion of the same, the shell I, located between the arms of the same, the incurving scrolls J, and the outwardly-curving scrolls K, arranged to lie against and conform to the circular edge of the back of the mirror, as shown in the accompanying drawing.

What is claimed as new is—

1. In the design herein set forth, the design for the back of a mirror or similar article, substantially as shown and described.

2. In the design herein set forth, the design for the handle of the back of a mirror or similar article, substantially as shown and described.

3. The design for the back and handle of a mirror or similar article, substantially as shown and described.

PHILEMON O. DICKINSON.
